UNITED STATES PATENT OFFICE.

CHARLES KOSTER, OF NEW YORK, N. Y.

BUILDING BLOCK AND WALL CONSTRUCTION.

Application filed October 17, 1925. Serial No. 63,085.

This invention relates to building construction and more particularly to a copper veneered building block and the method of making the same, though it is noted that the 5 invention is not limited to copper covered blocks, nor in some respects even to building blocks.

One object of the invention is to provide a building block of this kind which may be 10 easily and quickly laid by relatively unskilled labor and which will have a very ornamental appearance.

Another object of the invention is to provide a strong and well bonded structure or 15 wall construction utilizing said blocks.

Another object of the invention is to provide a method of manufacturing the blocks and of erecting the wall.

Other objects of the invention are to improve 20 generally the simplicity and strength of such structures and to provide a block of this kind which is strong and durable, and economical to manufacture and lay.

Still other objects of the invention will 25 appear as the description proceeds; and while herein details of the invention are described and claimed, the invention is not limited to these since many and various changes may be made without departing from the scope 30 of the invention as claimed in the broader claims.

The inventive features for the accomplishment 35 of these and other objects are shown herein in connection with an improved building block which, briefly stated, includes a metal shell open at the back and including top, bottom and end walls and a front wall, tie wires being secured to the front wall and projecting at the rear of the shell, and a body 40 of concrete filling said shell. Metal lath covers the back of the concrete.

As shown said blocks are laid on an iron 45 work frame to form a wall having mortar between adjacent brick. Rods disposed behind and spaced from said lath are tied to the blocks by said tie wire; and a backing of concrete is cast against the blocks and around said rods.

In the accompanying drawing, showing by 50 way of example, one of many possible embodiments of the invention.

Fig. 1 is a fragmental front elevation showing the blocks used in the construction of a wall;

55 Fig. 2 is a fragmental perspective view of the wall, partly in section;

Fig. 3 is a horizontal sectional view of the wall; and

Fig. 4 is a transverse vertical sectional view, showing the shell and tie wire before the concrete is cast in the shell and

Fig. 5 is a fragmentary perspective view showing a portion of the supporting structural iron frame work.

The outer part of my improved building 65 block 5 comprises a thin stamped-out block-shaped shell 6 (Fig. 4) of copper or other suitable material, open at the back 7 and including top and bottom walls 8 and 9, an ornamental front wall 10 and end walls 11 having 70 vertical grooves 12 (Fig. 2); though the invention is not limited to all five walls, since the front wall and only one or two other walls are absolutely necessary.

A pair of U-shaped tie wires 15 each has 75 its yoke part 16 soldered to the inner face of said front wall and has its free ends 17 projecting at the rear of the shell. An adhesive binder is applied to the inner face of the shell, and concrete 18 is cast into and fills the shell. 80 Expanded metal lath 19 covers the back of the concrete, behind which lath the tie wires 15 are tied as at 20 (Fig. 2).

Figs. 1 and 3 show a wall having windows 22 and as shown in Figs. 3 and 5 comprise a 85 frame work 23 of iron construction work or structural steel on the front of which said blocks are laid in suitable iron channels receiving the bottom row of the blocks, the joints of said frame work being put together 90 with insulating cement, if desired, in order that electrical disturbances may have no effect. A binder or mortar 24 (Fig. 2) of tar and cement is also applied between adjacent bricks or blocks and in said grooves 12. 95

Reinforcing rods 25 vertically disposed at intervals behind and spaced from said lath are tied to the block by said tie wires as at 26. After the blocks, to the height of one story are fastened in position as stated, a wooden or 100 iron form is erected on the inside, and the intervening space of about twelve inches is filled with concrete forming a concrete backing 27 cast against the back of the blocks and around said lath, rods and the tied ends of 105 the wires.

The blocks are formed by stamping out or otherwise providing metal shells having at least one open side, preferably the back, and soldering or otherwise securing the tie 110 wires 15 to the inner face of the front wall of the shells with their ends 17 projecting at

the rear of the shell after which an adhesive binder is applied to the inner face of the shell. If more than one wall of the shell is left out the shells must be placed in molds with the 5 open back uppermost for filling said shell with plastic concrete, but if all five walls are present, the mold need not be used.

Either before or after placing expanded metal lath 19 on the back of the concrete, said 10 blocks are laid on the frame work 23 with said mortar between adjacent blocks and in the grooves 12. The reinforcing rods 25 are placed behind and spaced from said lath and tied to the blocks by said tie wires 15.

15 After each story of the block is laid a form is erected just to the rear of said rods and a concrete backing is poured between the form and blocks against the back of the blocks and around the lath, rods and the tied ends of 20 the wires.

The blocks and wall construction when made as described meet the tests required by building departments, and the exterior of the shell may be treated with acids or other 25 materials for pleasing color effects.

I claim as my invention:

1. A wall block consisting of a hollow shell closed except at one of its sides, a filling in the shell conforming to the shape of the interior of the shell and enclosed by the shell except at one side of the filling which is exposed by the open side of the shell, and tie 30 means cooperating between the front side of the shell and the exposed side of the filling.

35 2. A wall block consisting of a hollow shell closed except at one of its sides, a filling in the shell conforming to the shape of the interior of the shell and enclosed by the shell except at one side of the filling which is exposed by the open side of the shell, tie means 40 cooperating between the front side of the shell and the exposed side of the filling, and metal lathing secured by said means to the exposed side of the filling.

45 3. In a wall block, a hollow shell closed at all its sides except its rear side and having securing means attached to the inner face of its front side.

50 4. In a wall block, a hollow shell closed at all its sides except its rear side and having securing means attached to the inner face of

its front side provided with end portions extending through the shell and outwardly from its open rear side.

5. In a wall block, a hollow rectangular 45 shell closed at its top, bottom, ends and front side and open at its rear side and having tie wires secured to the inner face of its front side provided with end portions extending through the shell and outwardly from its open 50 rear side.

6. A block comprising a body of hardened plastic material; a plate covering its front face; and tie means secured to said plate and passing through the rear of the body. 55

7. In a wall construction, adjacent blocks having securing means extending from the rear faces of the blocks; reinforcing means attached to the rear of the blocks by said securing means; and a plastic backing arranged 60 against the rear of the blocks and enclosing the reinforcing means and securing means.

8. In a wall construction, adjacent blocks having securing means extending from faces of the blocks; lathing attached to the rear of 65 the blocks by said securing means; and a plastic backing arranged against the blocks and enclosing the lathing and securing means.

9. In a wall construction, adjacent blocks 70 having securing means extending from the rear faces of the blocks; lathing attached to the rear of the blocks by said securing means; reinforcing devices disposed to the rear of the lathing and secured to the blocks by said 75 securing means; and a plastic backing arranged against the rear of the blocks and enclosing the reinforcing device and securing means.

10. In a wall construction, aligned blocks 80 having securing means extending from the rear faces of the blocks; reinforcing rods disposed to the rear of the blocks and secured to the blocks by said securing means; and a plastic backing arranged against the rear of 85 the blocks and enclosing the rods and securing means.

Signed at New York in the county of New York and State of New York this 15th day of October A. D. 1925.

CHARLES KOSTER.
